UNITED STATES PATENT OFFICE

SIGMUND L. LEDERER, OF PROVIDENCE, RHODE ISLAND, ASSIGNOR TO PROVIDENCE STOCK COMPANY, A CORPORATION OF RHODE ISLAND

DESIGN FOR A BRACELET CHAIN

Application filed June 24, 1930. Serial No. 36,154. Term of patent 3½ years.

To all whom it may concern:

Be it known that I, SIGMUND L. LEDERER, a citizen of the United States, residing in Providence, county of Providence, and State of Rhode Island, have invented a new, original, and ornamental Design for a Bracelet Chain, of which the following is a specification, reference being had to the accompanying drawing, forming a part thereof.

Fig. 1 is a plan view of a portion of a bracelet chain; Fig. 2 is a side elevation thereof; and Fig. 3 is a perspective view of one of the links of a bracelet chain, showing my new design.

I claim:

The ornamental design for a bracelet chain, substantially as shown.

SIGMUND L. LEDERER.
